UNITED STATES PATENT OFFICE

2,467,798

5,5'-DIHYDROXYDIAMYL ETHER

Kliem Alexander and Lester E. Schniepp, Peoria, Ill., assignors to the United States of America as represented by the Secretary of Agriculture

No Drawing. Application May 18, 1948,
Serial No. 27,816

1 Claim. (Cl. 260—615)

(Granted under the act of March 3, 1883, as amended April 30, 1928; 370 O. G. 757)

1

This application is made under the act of March 3, 1883, as amended by the act of April 30, 1928, and the invention herein described, if patented in any country, may be manufactured and used by or for the Government of the United States of America for governmental purposes throughout the world without the payment to us of any royalty thereon.

This invention relates to 5,5'-dihydroxydiamyl ether having the formula

and has among its objects the provision of this compound and a process for making it. This compound is useful as a plasticizer, as a chemical intermediate, and as a high boiling solvent.

According to our invention diesters of oxydivaleric acid are reduced with the aid of sodium and alcohol to produce the desired compound.

The ester starting materials may be prepared in accordance with the process described in the copending application Serial No. 27,817, filed May 18, 1948.

The following example is illustrative of the invention but is not intended to be limiting.

Preparation of 5,5'-dihydroxydiamyl ether

In a large flask provided with a reflux condenser was placed a solution containing 41.2 g. (0.15 mole) of diethyl oxydivalerate in 480 cc. of absolute ethanol. To this was added 42 grams (1.83 moles) of sodium in large pieces. Cooling in an ice bath was necessary during the first stages of the reaction. When the initial vigor of the reaction had subsided, the mixture was heated on a steam bath for several hours until all the sodium dissolved. Water (180 cc.) was then added to the cooled mixture and the alcohol distilled off. More water (250 cc.) was added

and the oil layer which separated was removed. Distillation at reduced pressure gave 5,5'-dihydroxydiamyl ether having the formula

5 as a colorless, viscous liquid, B. P. 141-142° C. (0.5 mm.); M. P. 16-18° C. It is soluble in water and ether, insoluble in benzene. The yield was 21 grams.

10 Other diesters of oxydivaleric acid, such as diethyl oxydivalerate, ditetrahydrofuryl oxydivalerate, and the like may be reduced in a manner similar to that described in the above example to form the desired product.

15 The procedure of the above example may be varied as to proportions of reactants and reaction conditions, these variations being apparent to those skilled in the art.

Although in the above example the reduction of the esters by means of sodium and alcohol is described, other means of hydrogenation, for example, catalytic hydrogenation, may be employed.

Having thus described our invention, we claim:

KLIEM ALEXANDER,
LESTER E. SCHNIEPP.
